UNITED STATES PATENT OFFICE.

HARRIET HILL, OF NEW YORK, N. Y.

PAPER-LINED RECEPTACLE.

1,213,194.

Specification of Letters Patent. Patented Jan. 23, 1917.

Application filed January 12, 1916. Serial No. 71,603.

To all whom it may concern:

Be it known that I, HARRIET HILL, a citizen of the United States, residing at New York, county of New York, and State of New York, have invented a new and useful Improvement in Paper-Lined Receptacles, of which the following is a specification.

This invention has relation to paper lined liquid holding receptacles, and has for its general object to provide certain constructions which will operate to adapt the receptacle to accommodate linings of various sizes and be readily converted from an article such as a finger bowl or wash basin into a holder for flowers, and further to admit of readily adjusting the lining to and detaching it from the receptacle. And to these ends the invention resides in providing the receptacle with a plurality of series of projections each series being arranged at a different height above the bottom of the receptacle from the other series, and in constructing the said projections so as to engage with the edge of the paper lining and to support a guard.

Other objects will appear and be better understood from that embodiment of my invention of which the following is a specification, reference being had to the accompanying drawings forming part hereof, and in which:

Figure 1, is a side elevation of the invention. Fig. 2, is a vertical cross sectional view. Fig. 3, is a detail side elevation partly in section, of a modified form of the device.

The construction forming the subject matter of this invention is arranged on the inner face of the receptacle. This receptacle may be an ordinary metallic wash basin such as is found in railway coaches, or it may be a metallic ink well, or as shown in the drawings, it may be an ordinary finger bowl or a device that may be converted from a finger bowl into a flower pot and conversely. As shown in the drawings the said construction is in the form of a projection 5, arranged on the inner surface of the receptacle 6. The projection may be made by any method and for purposes of illustration I have shown it as being up-struck, or in the form of a depending tongue. As will be noted by reference to the drawings, a plurality of these tongues are provided and it will be further noted that these are arranged in a plurality of circular series,

the tongues of each series being in alinement with those of the other series. Although this alinement of the tongues is ideal from a standpoint of symmetry it is by no means essential to this invention.

The lining for the receptacle is indicated by 8, and is made of water proofed paper. When this lining is arranged in the receptacle 6, and its upper edge adjusted underneath the tongues of one series these tongues will effectively hold the lining from being accidentally displaced. It will be noted that the series of tongues which engage the lining when this has been adjusted in the receptacle will depend upon the height thereof. As a consequence of this, linings of various sizes or heights may be used with the same receptacle. This feature is of great commercial importance in that an establishment, where finger bowls are used, is not, by reason of having previously procured bowls of a particular manufacture, restricted to the use of the linings prescribed for these, it being obvious that the present structure may be readily incorporated with any of the metallic bowls now in use and thereby adapt these to accommodate any of the standard sizes of paper linings now in the market.

It will be observed that with the present invention practically the entire edge of the lining is exposed when the bowl is in use, so that when it is desired to detach the lining from the receptacle a hold thereof with the finger and thumb of one hand may be readily taken at a point between any two adjacent tongues and the lining bent inwardly and downwardly until disengagement thereof with the tongues has been effected. This disengagement it will be observed is accomplished with great facility and without the use of an implement such as a fork.

In instances where it is desired to convert a finger bowl into a flower holding receptacle or where it is desired to provide a receptacle solely for holding flowers a guard in the form of disk 9, is employed. The circumference of the disk 9, corresponds to the circumference at that part of the receptacle 6, at which a series of tongues 5, are formed so that when the disk is inserted in the receptacle it will bear on and be supported by the said tongues. One or more openings 10, are formed in the disk through which the stems of the flowers pass and extend into the water in the lining 8. With this construction it will be obvious that when a plurality of

disks each of which corresponds in circumference to one of the series of tongues then flowers may be supported at various heights above the bottom of the lining. As a consequence of this flowers having relatively short or relatively long stems may be accommodated with the receptacle of this invention. In this connection it may be well to state that in instances where it is desired to use a paper lining in an ink well, a disk like that just described but smaller and provided with an opening for the pen point, may be employed with a metallic ink well formed with tongues arranged to support the said disk.

15 It will here be observed that the presence of the disk will limit the distance to which the pen point may be introduced into the ink well by having the opening in the disk smaller than the end of the pen holder.

20 With this construction and when the disk is arranged for a distance from the bottom of the lining greater than the length of the pen point, accidental puncture of the lining by the pen point upon inserting this in to the

25 ink, will be avoided.

It will of course be understood that any form of paper lining may be combined with the receptacle of this invention. The more common forms are what is known as the plain and the crimped. The use of the latter is preferred by reason of its odd appearance and its ability to expand radially and there-

by bind on the inner surface of the receptacle.

What is claimed as new is:

35 1. A liquid holding receptacle comprising a body open at its upper end, a paper lining conforming substantially to the shape of the receptacle and arranged therein, said receptacle having on its inner surface a series of 40 depending projections engaging the upper edge of the lining and a second series of depending projections disposed at a different distance from the bottom of the receptacle 45 from the first whereby to adapt the receptacle to secure therein linings of various sizes.

2. A liquid holding receptacle comprising a body open at its upper end, a paper lining conforming substantially to the shape of the receptacle and arranged therein, said receptacle having on its inner surface a plurality 50 of spaced projections disposed below the said upper end, and engaging the upper edge of said lining and a perforated disk arranged 55 on said projections.

In testimony whereof, I have signed my name to this specification, in the presence of two subscribing witnesses, this 11th day of January, 1916.

HARRIET HILL.
